Inventor:

Linus Paul Schindler.

Patented Apr. 17, 1928.

UNITED STATES PATENT OFFICE.

LINUS PAUL SCHINDLER, OF HAMBURG, GERMANY.

SAFETY DEVICE FOR PRINTING MACHINES.

Application filed September 2, 1924, Serial No. 735,504, and in Germany August 23, 1923.

This invention has for its object to improve the construction of the commonly used safety devices designed to prevent, in printing presses, the hand of the workman getting injured by getting between the printing cylinders. With this object in view a special positive connection is arranged between a guard of roller blind form and the device for starting or stopping the printing press. This connection is constructed so that the printing press cannot be started unless the guard has been pulled down completely.

Another object of the invention is the provision of means on said connection for preventing the printing cylinders jumping out of their position in the machine frame when said bearings should not have been properly fixed before the machine is started.

An embodiment of the invention is shown by way of example on the accompanying drawing which illustrates the safety device mounted on a fly printing press of known construction.

Fig. 1 shows the corresponding parts of the printing machine in side elevation.

Fig. 2 shows in plan view the pull rod with two projections and the corresponding bearings of the printing cylinders.

Fig. 3 shows on larger scale in side elevation, the outer side wall being removed, one of the curved guides for the guard.

Fig. 4 shows in plan view partly in section a portion of one of the curved guides with a portion of the guard.

Fig. 5 shows in section the crank and the ratchet mechanism.

On the side walls 1 of the front part of the machine frame two curved guides 2 of channel-shaped cross section are fixed which terminate each at the rear end in a box-shaped casing 3. A cross axle 4 is journaled in the upper ends of the guides 2 and serves for winding up the guard 5 similar to a roller blind which is made from canvas, wire gauze or other convenient material. The lower end of this guard 5 is attached to a cross rod 6 on each end of which a slide or carriage is fixed, said two carriages 7 being guided in the channel-shaped curved guides 2. The two slides or carriages have each two rollers 8 rolling on the upper and lower members of the corresponding channel-shaped guides. The guard 5 is wound up on the axle 4 through the action of a spring 9. In each casing 3 of the guides 2 two locking pawls 12, 13 are pivotally mounted on

a shaft 10 and a ratchet wheel 14 is further mounted on a shaft 11 extending across the machine frame. On one end of said shaft 11 projecting from one of the casings 3 a crank 15 is keyed which, through a rod 16, is connected with the starting lever 17 of the printing press. The locking pawl 12 engaging with the ratchet wheel 14 prevents shaft 11 from rotating and consequently the operation of the starting lever 17 so that in this case the starting lever 17 cannot be operated. Only when the guard 5 has been pulled down and the noses 18 of the carriages 7 have penetrated into the casings 3 the locking pawl 12 is raised and brought out of engagement with the ratchet wheel so that the shaft 11 is liberated and can be revolved. The carriages or slides 7 are locked in their position each by means of a hook 19 which grips over the cross rod 6. When the machine is now started by means of the starting lever 17 the second pawl 13 is raised through the intermediary of an eccentric disk 20 keyed on shaft 11 of the ratchet wheels so that the corresponding hook 21 of pawl 13 grips behind the stud 22 of the nose 18 of the carriages or slides 7. The carriages 7 are thus securely held during the working of the machine even when the hooks 19 are released or if they should be accidentally released. When the machine has been stopped the pawls 13 release the slides or carriages 7 so that on the releasing of hook 19, the guard 5 is pulled up or wound up through the action of spring 9.

The printing cylinders—not shown in the drawing—are removably mounted in the printing press. To remove the printing cylinders their bearings 24, which are diagrammatically shown in the Figs. 1 and 2, or the cover plates of these bearings, must be removed. These bearings 24 or their cover plates are fixed by means of screws. The axles of the printing cylinders are journaled in said bearings 24. If the workman should, for instance, forget to fix the screws for the cover plates of the bearings 24 after a fresh printing cylinder has been inserted, the printing cylinder might be thrown out of its bearing 24. In order to prevent this the connecting rod 16 has two projections 25, which, when the starting lever has been brought into the position for starting the machine, bear against the bearings 24 and serve as substitutes for the screws in securely holding the bearings 24 in their position.

The printing cylinders are further held by downwardly projecting arms 23 of the cross rod 6. When the machine is at rest, owing to the shifting of rod 16 as shown in Fig. 2, the bearings are released by the projections 25 and may be removed. The revolving guard 5 is forced by transverse rods 26 to adapt itself to the curvature of the guides 2 when it is being stretched. For the spring 10 9 a counterweight might be substituted. If instead of the starting lever 17 the machine has any other starting means the pull rod 16 must be connected with the same in a convenient manner so that the crank 15 is operated when the machine is being started.

I claim:—

A safety device for printing machines comprising in combination with the starting lever of the machine, a guard or roller blind 20 on a revolvable axle to which one end of said guard is attached, a cross rod in the free end of said guard, two carriages one at either end of said cross rod, two curved channel-

shaped guides on the machine frame in which said carriages are guided, a casing at the 25 lower end of said two curved guides, an axle journaled in each of said casings, ratchet wheels one in each casing keyed on said axle a spring controlled locking pawl pivotally mounted in each casing so that it is adapted 30 to engage with and lock the corresponding ratchet wheel, a nose on each carriage adapted to penetrate into the corresponding casing when the guard has been pulled down so that said nose disengages said pawl from the corresponding ratchet wheel, a crank arm on one end of said axle, a rod connecting said crank with said starting lever of the machine so that the operation of said starting lever is possible only when the pawl has 40 been operated by the pulled down guard, and means for locking the corresponding carriage of said guard during the working of the printing machine.

In testimony whereof I affix my signature.

LINUS PAUL SCHINDLER.
